(57) **CLAIM**

The ornamental design for a camping light, as shown and described.

DESCRIPTION

FIG. 1 is a first perspective view of a camping light showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof shown in an environment of use.

The broken lines shown in the drawings depict portions of the camping light that form no part of the claimed design. The additional broken lines shown in FIG. 9 depict environmental subject matter that forms no part of the claimed design.

1 Claim, 9 Drawing Sheets
